UNITED STATES PATENT OFFICE.

CHARLES M. MARTIN, OF NEW YORK, N. Y., ASSIGNOR TO THE WASHINGTON FIRE EXTINGUISHER MANUFACTURING COMPANY, OF WASHINGTON, DISTRICT OF COLUMBIA.

FIRE-EXTINGUISHER.

SPECIFICATION forming part of Letters Patent No. 246,895, dated September 13, 1881.

Application filed February 19, 1881. (No model.)

To all whom it may concern:

Be it known that I, CHARLES M. MARTIN, of the city and State of New York, have invented certain Improvements in Fire-Extinguishers; 5 and I hereby declare the following to be a full, clear, and exact description thereof, reference being had to the accompanying drawings, making part of this specification, in which—

Figure 1 is a vertical section of the extinguisher. Fig. 2 is a vertical section on the line *x x* of Fig. 1.

My invention relates to that class of fire-extinguishers known in the trade as "stationary tanks;" and it has for its object the facilitating of the mixing of the chemicals and the charging of the machine.

My invention consists of a tank provided with a small dome, combined with a swinging bucket suspended by chains passing to a crank-shaft crossing the said dome, and having a chain from its bottom to the side of the tank, all of which will be hereinafter more specifically described and claimed.

In order that those skilled in the art may 25 make and use my invention, I will proceed to describe the manner in which I have carried it out.

In the said drawings, A is the tank, B the dome, and C the plug which closes the charging-opening. Across the dome passes a crank-shaft, D, wound with two small chains, *a*, having their ends attached to trunnions *b* of a conical vessel, E, the upper edge of which has a flange, *i i*, of a slightly-larger diameter than 35 dome B. From the bottom or tip of the coni-

cal vessel E a chain, N, passes to some point, P, where it is secured to the inside of the tank. H is an opening for charging the body of the tank.

In charging the machine the dry chemicals 40 are put in the vessel E by removing the plug C, any proper stop holding the crank-shaft D in position after the bucket or conical vessel E is drawn up until flange *i* rests against the top of the tank and around the mouth of the 45 dome.

When it is desired to mix the chemicals the crank-shaft D is turned so as to allow the chains to run out, the vessel E descends, and, as chain N resists the movement of the bottom 50 of the vessel, it tips over and empties the chemicals into the body of the tank.

The construction described will be found to be highly advantageous in tanks for village engines, as, when flange *i* is drawn tightly up 55 against the top of the tank, none of the liquid in the body of the tank can be splashed into the dry chemicals by the motion or jolting of the engine.

Having thus described my invention, what 60 I claim as new, and desire to secure by Letters Patent, is—

Tank A and dome B, in combination with suspended vessel E, crank-shaft D, chains *a a* and N, substantially as described, and for the 65 purpose set forth.

CHAS. M. MARTIN.
